PENCIL SHARPENER

Irwin E. Cohn and Wilfred E. Tait,
New York, N. Y.

Application January 28, 1935, Serial No. 3,780

2 Claims. (Cl. 120—96)

The object of the present invention is to provide a pencil sharpener which will be thoroughly effective in use and at the same time embody a minimum of parts as compared with devices of 5 the type now in use, due to a discovery made by us that a single spiral cutter and a rack raceway may be so positioned and associated with each other and with an abutment plate opposite the spiral cutter that bodily rotation of the cutter and plate in unison will cause rotation of the cutter by direct engagement of its spirals and the rack raceway.

The invention will be described with reference to the accompanying drawing, in which

15 Fig. 1 is a view in sectional elevation of an embodiment of the invention, the section being on the line 1—1, Fig. 4.

Fig. 2 is a horizontal section on the line 2—2, Fig. 4.

20 Fig. 3 is a front end elevation of the device, partly broken away.

Fig. 4 is a vertical section on the line 4—4, Fig. 3.

The device comprises a base member 1 of sheet 25 metal which supports the horizontal flanges 2x, 3x, of opposed vertical plates 2 and 3. Plates 2 and 3 are rounded at their top and the edges thereof are inturned to form the flanges a. Plates 2 and 3 are connected by side spacer plates 4 and 30 top spacer bar 4x and a metal drawer 5 is disposed below plates 4. A celluloid or similar flexible cover 6 rests upon top spacer bar 4x its end extending downwardly and being held by the side spacer plates 4, opposed lips at the upper margin of said plates holding the edges of the 35 flexible cover in position, as shown in Fig. 1.

Mounted upon vertical plate 2 is a circular rack affording a raceway for the spiral cutter. The rack is stamped from a single piece of sheet 40 metal having a vertical face 7 and peripherally disposed angularly bent arms 1x, the end of each arm entering a slot formed in vertical plate 2 and being bent over upon the outer face of said plate, as shown more particularly in Fig. 4.

45 Concentrically of the rack member 7, plate 2 is formed with a flanged aperture at 8 affording a bearing member for a stud shaft 9 carrying the cutter bracket 10.

The cutter bracket is a U-shaped piece of sheet 50 metal having two arms 11 and 12, one arm being mounted on shaft 9 and the second arm being mounted on a sleeve 13 which enters a flanged aperture formed in plate 3 at 14. Bent at right angles to arms 11 and 12 from bracket 10 are 55 opposed extension flanges 15 which receive and

support a pencil guide plate 16 having a tapered channel at 16x.

Guide plate 16 is opposite a spiral cutter 17 rotatably mounted on a pin 18 held by arms 11 and 12. The spirals of cutter 17 directly engage and therefore mesh with the teeth of annular rack 7, 1x, as shown more particularly in Fig. 1.

Threaded upon exposed end of stud shaft 9 is a crank 19 by which cutter bracket 10 may be rotated.

10 Pencil guiding plate 16 and spiral cutter 17 are reversely inclined being spaced the maximum distance adjacent sleeve 13. The sleeve receives and guides a pencil and thus the receiving end of plate 16 is disposed at one side of the sleeve 15 opening and the receiving end of the cutter is disposed opposite thereto and also at the side of the sleeve opening.

15 By this construction, the entire side of the pencil opposite the cutter is firmly held during 20 the cutting operation, as distinguished from a construction wherein two opposed spiral cutters are used and the two cutters act in opposition by rotation upon the pencil.

In spite of the simplicity of our construction, 25 it is found that a better result is obtained through the use of our device than in the use of a more complicated structure. If a pencil is inserted in sleeve 13 and slight pressure imparted thereto during rotation of crank 19, cutting will be initiated and as the tapering of the pencil progresses by the cutter plate 16, the pencil will be held firmly and will be accurately guided relatively to the rotary cutter as the tapering progresses. The pencil being lightly held, it will 30 occasionally be partly rotated by the action of the rotary cutter and hence it will be given an even 35 tapered point.

Having described our invention, what we claim and desire to secure by Letters Patent, is as 40 follows:—

1. A pencil sharpener comprising opposed vertical plates, a sleeve carried by one plate, a stud shaft rotatably carried by the second plate, a handle mounted upon said stud shaft, a bracket 45 comprising a piece of sheet metal having sections at its ends bent to form opposed arms, one arm being mounted on the stud shaft and one arm on the sleeve, a pencil-guiding abutment carried by the bracket at its section intermediate said arms, 50 a spiral toothed cutter rotatably mounted on the arms opposite said abutment, and an annular rack carried by one of said vertical plates and having its teeth directly in mesh with the spirals of said cutter.

2. A pencil sharpener comprising opposed vertical supports having inner and outer faces, an annular rack projected a substantial distance inwardly of and carried by one of said supports, said vertical support being provided with a bearing concentrically of said rack, a bracket having opposed arms, a spiral toothed cutter rotatably mounted on the said arms, a bearing member carried by the bracket and supporting one of the bracket arms intermediate the rack and one of its vertical supports with the teeth of the cutter

- 10

directly engaging the teeth of the rack, a pencil-guiding abutment carried by the bracket, a pencil-receiving aperture in one of the bracket arms intermediate said abutment and the spiral toothed cutter, a bearing for the bracket, and a pencil-receiving aperture afforded by the second vertical support, and means for rotating the bracket.
